DESIGN FOR A CONDIMENT BOTTLE

Alfred J. Flauder, Trumbull, Conn.

Application December 12, 1942, Serial No. 109,025

Term of patent 7 years

To all whom it may concern:

Be it known that I, Alfred J. Flauder, a citizen of the United States, residing at Trumbull, in the county of Fairfield and State of Connecticut, have invented a new, original, and ornamental Design for a Condiment Bottle, of which the following is a specification, reference being had to the accompanying drawing forming part hereof.

Fig. 1 is a top plan view of a condiment bottle, showing my new design;

Fig. 2 is a side elevational view of the same;

Fig. 3 is a view similar to Fig. 2 but taken at right angles thereto.

I claim:

The ornamental design for a condiment bottle, substantially as shown.

ALFRED J. FLAUDER.
